ATTORNEYS.

Patented Nov. 8, 1927.

UNITED STATES PATENT OFFICE.

CHARLES M. COLE, OF OAKLAND, CALIFORNIA.

WAFFLE IRON.

Application filed August 16, 1926. Serial No. 129,525.

This invention relates to waffle irons and has for one of its objects the provision of a simple, economical and efficient waffle iron.

Another object of my present invention is the provision of a device of the character mentioned which, by its construction is economical of the electrical energy to heat it.

With the foregoing objects in view, together with such other objects and advantages as may subsequently appear, this invention resides in the construction and arrangement of parts hereinafter described and claimed, and illustrated in the accompanying drawing.

The drawing shows in side elevation a waffle iron of three co-operating sections, the same being in open position. In more detail the waffle iron comprises mold sections 3, 4 and 5, with adjacent mold sections at their rear ends, as indicated at 7 and 8, so that they may be separated as shown in the drawing, when raised by means of the handles 10 which are perforated so that they will not become too hot.

The sections 3 and 5 are provided respectively with mold surfaces 3^a and 5^a, while the mold section 4 is provided with opposing mold surfaces 4^a and 4^b, which respectively co-operate with the mold surfaces 3^a and 5^a.

Electrical conductors 12, 13, 14 and 15 are provided for heating the molds. The elec-

trical conductors 12 and 13 are in series with each other, while the electrical conductors 14 and 15 are in series with each other. The electrical conductors 12 and 13 are in parallel with the conductors 14 and 15. The terminals of the electrical conductors are secured to a selective switch 17. To the switch 16 is connected a power line 18. The switch 17 is adapted to turn the electrical current on to heat either the conductors 14 and 15 at one time, or all of the conductors simultaneously.

It will be noted that the sections 3, 4 and 5 in their normal positions are superimposed upon each other. This arrangement provides for greater economy of the heat derived from the electrical current, as will be readily appreciated.

While I have described one embodiment of my invention, modifications thereof may be readily devised without departing from the spirit of my invention, and it is to be understood that such modifications come within the scope of the appended claim.

I claim:

A waffle iron comprising at least three superposed mold sections adapted to be electrically heated, the intermediate section having mold surfaces on its upper and lower surfaces respectively.

CHARLES M. COLE.
